UNITED STATES PATENT OFFICE.

THOMAS MANAHAN, OF NEW YORK, N. Y.

APPARATUS FOR COATING PAPER AND OTHER MATERIAL.

SPECIFICATION forming part of Letters Patent No. 399,544, dated March 12, 1889.

Application filed September 13, 1888. Serial No. 285,324. (No model.)

To all whom it may concern:

Be it known that I, THOMAS MANAHAN, a citizen of the United States, residing at New York, in the county and State of New York, 5 have invented new and useful Improvements in Apparatus for Coating Paper and other Materials, of which the following is a specification.

This invention has for its object to provide 10 novel, simple, and efficient mechanism for uniformly and properly supplying a fluid—such as oil, asphaltum, or other substance—to the under surface of a web of paper, parchment, or like material traveling over the uppermost 15 portion of a roller that delivers the oil or other substance to the web.

The object of my invention I accomplish by 20 the features of construction and combination and arrangement of devices hereinafter 25 scribed and specified in the claims, reference being made to the accompanying drawings, illustrating my invention, in which—

Figure 1 is a plan view of the apparatus. Fig. 2 is a section along the line $x-x$, Fig. 1.

25 Similar letters indicate corresponding parts.

In the drawings, the letter A indicates a frame or support. On a roller, B, is wound a web or sheet, C, of paper or other material. From this web-carrying roller B, the web or 30 sheet passes to a tension-roller, D, and to a delivery-roller, E, supplied with a suitable substance—such as oil or asphaltum—from a trough, F. From the delivery-roller E the web or sheet C passes to a tension-roller, G, 35 and to the scrapers H. The distributing-roller I causes the substance to be distributed evenly or uniformly over the sheet C. The treated sheet C is wound up on the receiving-roller K.

The scrapers L M remove the surplus substance from the delivery-roller E and the scrapers H remove the surplus substance from the sheet. The drip-board Q leads the surplus substances removed by the scrapers H back into the trough F. The roller E has a 45 covering, N, of absorbent material—such as felt—and the scrapers H have their scraping-edges provided with a soft covering, O, such as felt. The scrapers H are thus not likely to cut or injure the sheet C, which, when moist 50 or saturated with the substance from the trough F, is frail and easily injured. The

distributing-roller I has a covering, P, of absorbent material, such as felt.

The scrapers H are adjustable vertically independently of each other along ways formed by arms R, and said scrapers can be adjusted along said ways to different heights or levels by being made to rest on pins S, inserted in holes in the arms R. By having each scraper H adjustable along its way independently of the other scrapers the scraping operation can be accurately regulated. To provide tension of the sheet C, a brake-band, T, is provided for the web-carrying roller B. Said brake-band T is secured at U, and a screw, V, worked 65 by a handle or hand-wheel, W, can tighten the brake-band. The power for winding up the sheet being applied to the receiving-roller K and the brake being properly tightened on the web-carrying roller B, the sheet C is subjected 70 to the proper degree of tension during the operation. Any suitable device—such as a belt, g, Fig. 1—applied to a pulley can be made to actuate the receiving-roller K, and a shifter or clutch-lever, h, can be applied in any well-known suitable way to stop or start the receiving-roller.

The trough F hangs upon the cords or straps X, one of which passes over the guide-roller Y to the rotary shaft Z, where said strap is secured, while the other strap is secured directly to the rotary shaft Z. By turning the rotary shaft Z in one direction or another the trough F can be raised or lowered, so as to be brought into proper position relative to the roller E. A handle or hand-wheel, a, can be used to actuate the rotary shaft Z, and a ratchet, b, and pawl c can be applied to hold the rotary shaft Z stationary.

The trough F can be emptied through the 90 stop-cock e into the trough d, whence the substance can be drawn off into any desired receptacle through the stop-cock f.

What I claim as new, and desire to secure by Letters Patent, is—

1. The combination, with a trough, F, and a delivery-roller, E, rotating therein, and over which the web passes, of a tension-roller, G, above the trough, and under which the web passes, a web-receiving roller, K, and the soft-ened scrapers H, adjustable in a vertical plane 95 to different heights between the tension and

web-receiving rollers and constituting a support for the web, over and against which the latter travels, substantially as described.

2. The combination, with a trough, F, a delivery-roller, E, and rollers for feeding a web over the delivery-roller, of arms R, arranged to form guideways, a series of scrapers, H, adjustable vertically independent of each other in said guideways, and pins S, for supporting the scrapers at different heights, substantially as described.

3. The combination, with a delivery-roller, E, and rollers for feeding a web over the same, of the trough F, the straps X, suspending the trough, the strap-supporting guide-roller Y, and the rotary shaft Z, connected with the straps for winding and unwinding the same to raise and lower the trough, substantially as described.

20 4. The combination, with a web-carrying roller, B, a trough, F, a delivery-roller, E, over which the web travels, a web-receiving roller, K, and tension-rollers, of a brake-band, T,

passing around a part of the web-carrying roller, and a lengthwise-adjustable screw, V, 25 connected with one end of the brake-band, and having a handle, W, for rotating it, substantially as described.

5. The combination, with a trough, F, a delivery-roller, E, over which the web passes, 30 and a web-receiving roller, K, of softened scrapers H, located between the delivery and web-receiving rollers, and constituting a supporting-rest over which the web passes, and a distributing-roller, I, having an absorbent 35 covering, P, and rotating in bearings between the guides and web-receiving roller, substantially as described.

In testimony whereof I have hereunto set my hand and seal in the presence of two subscribing witnesses.

THOMAS MANAHAN. [I. S.]
